UNITED STATES PATENT OFFICE.

JOSEPH PASSENO, OF WASHINGTON, DISTRICT OF COLUMBIA.

ROWLOCK.

SPECIFICATION forming part of Letters Patent No. 287,155, dated October 23, 1883.

Application filed August 23, 1883. (No model.)

To all whom it may concern:

Be it known that I, JOSEPH PASSENO, a citizen of the United States, residing at Washington, in the District of Columbia, have invented certain new and useful Improvements in Rowlocks, of which the following is a specification, reference being had therein to the accompanying drawings.

My invention relates to rowlocks for boats; and it consists in certain improvements in the same, to be hereinafter described in the specification and claims and shown in the drawings.

The objects of my invention are, first, to provide a rowlock having the minimum amount of metal, and at the same time to obtain the maximum of strength; second, to produce a lock that will turn readily on the pivot-pin, to allow the oar to trail at the side of the boat, whether attached to the gunwale or to an outrigger; third, to turn in like manner inward, to enable the oar to be shipped inboard; and, fourth, to obtain rigidity and firmness of the lock when the stroke is made. These several objects I accomplish by the means shown in the accompanying drawings, in which—

Figure 1 shows my rowlock attached to a gunwale-boat. Fig. 2 is a detached view of the lock or holder. Fig. 3 is a view of the gunwale-plate, brace, and pivot-pin, the lock or holder being removed. Fig. 4 is the gunwale-plate by which the lock is attached to the boat and held in position. Fig. 5 is a view of the brace detached, and Fig. 6 shows the plate attached to an outrigger-boat.

A is a metallic plate, designed to rest on the top of the boat's gunwale or on the ends of an outrigger, and it is provided with a shoulder, B, bent down at a right angle against the inner side of the gunwale and attached to the same by two or more screws, b b.

In the upper part of the plate A are three openings, a, c, and a'. These are preferably made square, and the central opening, c, receives the pivot-pin D, which is rigidly secured to the plate, and on the pin D is placed the lock or holder E, shaped as shown in the drawings, its forward arm, e, being made thick, to contain the thimble opening or socket f, which fits over the pivot-pin D, which latter reaches about half-way up in the socket of E. The rear arm, e', of the lock E swings clear of

the plate; but the front arm, e, is elongated at the bottom and rests on the plate, and thus provides a secure bearing or support.

In the front opening, a, of the gunwale-plate 55 is inserted the square shank of the brace G, provided with a shoulder, g, which rests on the plate, and the shank passes through the gunwale H, and has a nut, I, on the under side, which screws up against the gunwale and 60 secures the plate A to the gunwale, and keeps the lock in position. The brace G is bent over backward, at the height of the thimble or socket f, into a hook, J, which hook enters the thimble until it meets the top of the pivot-pin, 65 thus preventing the lock being raised from the pin, and at the same time giving additional strength and support to the lock during the stroke.

It will be seen that when the nut I is screwed 70 up it binds the plate and gunwale securely together by the pressure of the shoulder g of the brace against the superior surface of the plate, and the hook prevents the escape of the lock from the pivot-pin and imparts greater strength 75 to the lock, as, practically, it gives it two bearings.

The opening a' in the plate is to enable the brace to be reversed for the left-hand gunwale, so that the same plate may be used on 80 either side of a boat.

As the vertical portion of the brace is of the same height as the socket in the front arm, e, of the lock, it prevents its rising on the pivot-pin and obviates all wear, as well as preventing the disagreeable noise or creaking always 85 heard when a rowlock plays on its swivel.

When attached to an outrigger, the plate A usually becomes the top bar or rod which connects the two branches of the outrigger at the 90 ends farthest from the boat, and has no shoulder, and the pivot-pin may be connected with the plate by a nut and screw-thread, as is the brace in the previous instance, and the nut on the end of the brace will screw up against the 95 inferior surface of the bar or connecting-rod of the branches of the outrigger, as shown in Fig. 6 of the drawings.

I dispense entirely with the use of springs or guards at the top of the holder, as my rowlock 100 cannot possibly become accidentally detached from the boat and lost overboard.

Having thus described my invention, what I claim therein as new, and desire to secure by Letters Patent, is—

1. A rowlock pivoted on a pin rising from 5 and secured to a plate attached to the gunwale of a boat, said pin entering a thimble or socket in one arm of the lock, and the lock being held in place and strengthened by the hooked end of a brace entering the top of the socket, while 10 its lower end passes through the said plate and the gunwale of the boat, and is secured thereto by a nut or equivalent device.

2. The combination, in a rowlock, of the holder E, having its front arm provided with 15 a socket to receive the pivot-pin, the pivot-pin D, the brace G, having shoulder *g* and hook J, and the plate A, perforated, as described, with the gunwale of a boat, all substantially as shown and described.

20 3. A rowlock consisting of a holder, E, having a socket in its front arm, *e*, to receive the pivot-pin, in combination with the plate A, said plate being provided with a pivot-pin,

and the brace G, having a shoulder, *g*, and the hooked end J, the latter bent to enter the top 25 of the socket and hold the lock securely, all as described and shown.

4. A rowlock having the holder E socketed in its front arm to receive a pivot-pin, in combination with the plate A, attached to the ends 30 of an outrigger for row-boats, said plate having a pivot-pin entering the socket in the holder, and the brace G, provided at its lower end with a shank to pass through the plate, and a nut or equivalent means at the lower 35 end of the shank to secure the brace to the plate, and at its upper end a hook, J, to enter the top of the socket in the holder and secure the same on the pivot-pin, all substantially as hereinbefore shown and described.

In testimony whereof I affix my signature in presence of two witnesses.

JOSEPH PASSENO.
